United States Patent Office

Des. 206,262
Patented Nov. 22, 1966

206,262

TRAILER

Richard E. Ten Eyck, Wichita, Kans., assignor to Tryco Manufacturing Company, Inc., Decatur, Ill., a corporation of Illinois

Filed Mar. 9, 1966, Ser. No. 1,367

Term of patent 14 years

(Cl. D14—3)

FIG. 1

FIG. 2

FIGURE 1 is a top plan view of my design of a trailer;
being a mirror image thereof;
FIGURE 3 is a front elevational view; and

The dominant features of the design are shown in full line in the drawings.

I claim:

The ornamental design for a trailer, as shown and described.
